(57) **CLAIM**

The ornamental design for a compact hunting device, as shown and described.

DESCRIPTION

FIG. 1 is a perspective view of a hunting component showing my new design;

FIG. 2 is a front view thereof;

FIG. 3 is a side view thereof;

FIG. 4 is a rear view thereof;

FIG. 5 is a side view thereof;

FIG. 6 is a top view thereof; and;

FIG. 7 is a bottom view thereof.

The broken lines in FIGS. 2, 6, and 7 are included for the purpose of illustrating a portion of the claimed design that forms no part of the claimed design.
